SUPERHEATER

George S. Blankenhorn, Pasadena, Calif.

Application June 26, 1933, Serial No. 677,606

5 Claims. (Cl. 122—481)

The present invention relates in general to improvements in the art of generating steam, and relates more specifically to improvements in the construction and operation of steam superheaters 5 adapted for cooperation with boilers of various types.

Generally defined, an object of the present invention is to provide an improved steam superheater which is simple and compact in construction, and which is moreover highly efficient in 10 operation.

It has heretofore been proposed to provide various forms of superheaters adapted for direct cooperation with the so-called locomotive 15 type of fire tube boiler, and perhaps the most practical of these relatively inefficient prior devices, is a superheater wherein a number of auxiliary steam confining and superheating pipes are disposed directly within the delivery portions of 20 enlarged flues or fire tubes extending longitudinally through the boiler, and are connected to headers disposed within the smoke box beneath the stack. This prior superheating device however possesses numerous objectionable features 25 including the following. In order to accommodate the superheater piping and headers, the boiler must be specially constructed originally, and the device cannot be installed in standard 30 boilers of various types. The installation of this prior device makes it impossible to remove soot and the like from within the boiler tubes or flues wherein the superheater elements are located, and it is also impossible without disturbing the 35 superheater elements, to clean the external or water sides of the boiler flues since the ordinary rattler cannot be utilized for scale removal. The use of this prior superheater also necessitates enlargement of the smoke box for insertion of the 40 superheater headers, and the special large boiler flues cannot be rerolled without removing the superheater elements therefrom. The prior device furthermore is not conveniently and automatically drainable, and because of the location 45 of the heat transfer pipes within low temperature discharge portions of the fire tubes, a great amount of surface and long pipes are required thereby making the apparatus very costly. A boiler adapted to accommodate one of these prior 50 superheaters must also be provided with properly proportioned and disposed smaller flues, in addition to the large tubes containing the superheater elements, in order to effect proper distribution of the hot gases through all of the tubes in the boiler, and since these small flues are considerably smaller than those ordinarily used, they

materially restrict the available draft making the latter insufficient to compensate for the restriction and thus greatly reducing the boiler capacity. These and other objectionable features are present not only in the particular type of prior steam 5 superheater for locomotive boilers specifically referred to, but are also found in other prior devices of this kind which are associated directly with the boiler, thus making the prior apparatus relatively undesirable, complicated, inefficient 10 and expensive.

It is a more specific object of the present invention to provide improved steam superheating apparatus which obviates all of the above-mentioned objectionable features, and which may be 15 conveniently applied to any standard fire box boiler with only minor changes which can be readily made in the field.

Another specific object of the invention is to provide an improved device capable of producing 20 a high degree of superheat with a relatively small amount of heat transfer surface.

A further specific object of the invention is to provide an improved superheater which can be 25 readily installed by any boiler maker, and wherein the heat transferring elements may be easily replaced and attached to the distributing headers, and are effectively braced when assembled.

An additional specific object of the invention is to provide superheating apparatus in which 30 no damage will result from bursting of the steam confining elements, and wherein the various passages may be conveniently and completely drained.

Still another specific object of the invention 35 is to provide an improved superheater so constructed that regulation of the degree of superheat will take place automatically, and wherein the amount of superheat may be quickly varied either by increasing or decreasing the heat transfer surface, or by merely changing the location 40 of the heat transfer elements through simple adjustment of parts.

Another specific object of the invention is to provide an improved steam superheater which 45 automatically floods itself when the boiler is shut down, thus eliminating danger of damaging the heat transfer elements by burning during restarting with a hot fire.

A further specific object of the invention is to 50 provide a superheating device wherein no gaskets or ground joints are required at undesirable places, and in which no undesirable welded joints are required between the steam conducting conduits, thus meeting with the most highly ap- 55

proved present day practice and boiler design codes.

Still another specific object of the invention is to provide an improved superheater which can be installed primarily within the fire-box of a boiler, thereby permitting unobstructed cleaning and replacement or re-rolling of the boiler flues, and also enabling transportation of the boiler as a unit without disturbing the superheater.

10 An additional specific object of the invention is to provide an improved steam superheating system wherein the conduits and pipes are effectively protected against leaks due to expansion and contraction.

15 Another specific object of the invention is to provide an improved furnace construction especially cooperable with a superheater disposed within the fire box of a boiler, and adapted to most effectively distribute the heat so as to increase the superheater capacity and efficiency to a maximum.

20 A further specific object of the invention is to provide various improvements in the construction and in the mode of operating superheaters, whereby the cost of construction, installation and maintenance is reduced to a minimum, whereas the capacity and efficiency are enhanced to a maximum.

25 These and other objects and advantages will be apparent from the following detailed description.

30 A clear conception of embodiments of the various novel features, and of the mode of constructing and of operating the improved superheaters and boilers equipped therewith, may be had by referring to the drawings accompanying and forming a part of this specification in which like reference characters designate the same or similar parts in the several views.

35 Fig. 1 is a somewhat diagrammatic part sectional side elevation of a locomotive type of boiler having one form of the improved superheater applied thereto;

40 Fig. 2 is a transverse vertical section through the fire-box of the boiler and through the superheater of Fig. 1, taken along the line 2-2;

45 Fig. 3 is a top view of the boiler and superheater of Figs. 1 and 2;

50 Fig. 4 is an enlarged section through a fragment of the boiler and one of the superheater portions taken along the line 4-4 of Fig. 5;

55 Fig. 5 is a side elevation of the superheater portion of Fig. 4;

Fig. 6 is a part sectional top view of the boiler fragment and superheater portion, the section being taken along the line 6-6 of Fig. 5;

Fig. 7 is a similarly enlarged section through a fragment of the boiler and a modified form of superheater structure;

60 Fig. 8 is a top view of a boiler having a modified form of superheater assemblage associated therewith;

Fig. 9 is a part sectional side elevation of the boiler and modified superheater of Fig. 8;

65 Fig. 10 is a part sectional side elevation of a boiler having still another form of superheater applied thereto;

Fig. 11 is a rear view of the boiler and superheater of Fig. 10;

70 Fig. 12 is a fragmentary part sectional side elevation of a boiler having a further modification of the improved superheater applied thereto;

75 Fig. 13 is an enlarged transverse section through one of the superheater elements, the sec-

tion being taken along the line 13-13 of Fig. 1; and

Fig. 14 is a similar section through the superheater element, taken along the line 14-14 of Fig. 1.

80 While the invention has been shown and described herein as being specifically applied to a locomotive type of fire-tube boiler especially adapted for oil field service, it is not intended to limit the scope by such specific disclosure, since some of the features may obviously be applied to superheaters for other classes of service.

85 Referring to the embodiment of the invention illustrated in Figs. 1 to 3 inclusive, the boiler is of relatively standard construction comprising a substantially cylindrical horizontally disposed shell 15 having front and rear tube sheets 16, 17 therein; a smoke box 18 located within the front portion of the shell 15 and communicating with a stack in the usual manner; a plurality of substantially horizontal fire-tubes or flues 19 connecting the tube sheets 16, 17; a fire-box 20 located within the rear portion of the shell 15 and having a combustion chamber communicating with the rear ends of the flues 19; a fire-brick lined furnace 21 disposed directly beneath the fire box 20 and either above or below the ground line; and another brick lined pit 22 normally covered by a grating (not shown) and located rearwardly of the pit 21, the second pit 22 having a valve controlled gas line 23 extending therethrough and being omitted when the furnace is above the ground line. The top of the boiler shell 15 is provided with the usual steam dome 24, and the space surrounding the flues 19 and the fire-box 20, is supplied with water in a well-known manner. The rear portion of the fire-box 20 is also provided with an inspection opening normally closed by a door 25, and the gas line 23 has a burner 26 associated with its delivery end and disposed within the air supply opening 27 at the lower end of the rear wall of the pit 21. All of the foregoing structure is relatively standard, and comprises the important elements of the boiler installation which is shown 90 more or less diagrammatically in the drawings.

95 The improved superheater specifically illustrated in Figs. 1 to 6 inclusive and in Figs. 13 and 14, consists of two portions or sections, one of which is disposed on each side of the fire-box 20, and both of which communicate with the steam dome 24 and with a common steam delivery pipe, in a manner subsequently described. Each of the superheater sections comprises a substantially vertical rear inlet header 28, a substantially vertical front discharge header 29 spaced from and disposed somewhat lower than the corresponding inlet header 28, and a series of S-shaped tubular heat transfer elements 30 connecting the headers 28, 29 and having horizontal superimposed substantially parallel portions. The headers 28, 29 are located outside of the boiler adjacent the fire-box 20, and the elements 30 extend laterally from these headers through stay-tubes 31 permanently connecting the fire-box side walls with the outer boiler wail, into the combustion chamber wherein the horizontal elongated portions of the elements 30 are located. The heat transferring horizontal portions of the S-shaped elements may be spaced at any desired distance, 100 from the inner surfaces of the side walls of the fire-box 20, dependent upon the degree of superheating required, but the central and top portions of the combustion chamber are preferably maintained free from obstruction so that the hot 105

gases of combustion are free to enter the central and top flues 19, as will be apparent from Fig. 2.

The upper end of each inlet header 28 is connected by a curved pipe 32, to a common steam supply pipe 33 communicating with the steam dome 24, and the pipe 33 has a control valve 34 therein adjacent to the dome. The upper end of each discharge header 29 is likewise connected by a curved pipe 35, to a common delivery pipe 36 through a pipe fitting 37 mounted forwardly of the dome 24 and having a safety valve 38 associated therewith. The final delivery pipe 36 may also be provided with a control valve 39 and is adapted to conduct the superheated steam to any desirable source of utilization. It should be noted that the steam pipes 32, 33, 35, 36 are preferably gradually curved at the bends therein, in order to compensate for expansion and contraction thereof due to changes in temperature, thereby eliminating possibility of leakage.

The headers 28, 29 may be constructed and supported as shown in Figs. 4, 5 and 6, and one of these headers on each side of the boiler should be provided with a readily accessible drain valve. Each of these headers 28, 29 has the adjacent ends of the tubular elements 30 attached thereto by rolling or otherwise, through openings which are subsequently closed by plugs 40, and a channel bar 41 is attached to the side of each header by welding or otherwise, as shown in Figs. 4 and 6. This channel bar 41 is penetrated by the tubular elements 30, some distance away from the corresponding header 28, 29, thereby relieving the joints from lateral pressure and assisting in the support of the superheater elements 30. An attaching bar 42 is secured to the upper outer portion of each channel bar 41 by welding or otherwise, and a reaction bar 43 is likewise secured to the lower outer face of each bar 41, the upper bar 42 being slotted for adjustable attachment to the outer shell 15 of the boiler with the aid of cap screws 44 as indicated in Figs. 5 and 6. The position of the superheater elements 30 within the combustion chamber, may obviously be varied by virtue of the slots in the bars 42, and by inserting shims of various thickness between the bars 42, 43 and the adjacent boiler shell 15, in order to vary the degree of superheat and to secure maximum efficiency.

If so desired, the stay-tubes 31 may be omitted as in Fig. 7, and the superheater elements 30 may be rolled and expanded into firm engagement with the boiler shell 15 and the adjacent wall of the fire-box 20 as indicated at the joints 45, 46. These rolled joints 45, 46 will additionally assist in supporting the superheater, although the use of the stay-tubes 31 will permit more convenient adjustment of the superheater portions relative to the boiler.

The lower coils of the superheater may also be protected against the hottest flame, by providing a covering 47 as shown in Figs. 1, 2 and 4, and the elongated horizontal portions of the heat transfer elements 30 may be provided with front and rear braces 48, 49 shown generally in Fig. 1 and more in detail in Figs. 13 and 14. The forward braces 48 shown in Fig. 14, are forked and adapted for insertion between the adjacent superimposed portions of the element 30, while the rear braces 49 shown in Fig. 13, have hooked ends adapted to prevent spreading of the superimposed element portions. These braces 48, 49 may be applied after the superheater has been installed, and to various sections of the elements 30.

In order to improve the delivery of hot gases toward the superheater elements and to utilize the radiant heat in a most effective manner, the floor of the pit 21 may be formed as shown in Figs. 1 and 2, with a tapered deck 50. This deck 50 will direct the hot gases and the radiant heat from the lower portion of the pit 21 upwardly and outwardly directly toward the heat transfer elements 30, in an obvious manner. The deck 50 may be formed with more or less slope in order to most effectively radiate the heat.

While it is desirable, in order to secure most effective superheating, to have the elements 30 exposed to the hot gases within the fire box, the disposition of the inlet and discharge headers 28, 29 communicating with the elements 30, may be varied to a considerable extent. In the modified superheater of Figs. 8 and 9, the inlet and discharge headers 28', 29' are disposed on opposite sides of the boiler adjacent the smoke-box 18, and the heat transfer elements 30' extend through superimposed side flues 19 of the boiler into the fire-box 20 adjacent the opposite side walls thereof. The headers 28', 29' are constructed substantially as previously described, and the inlet headers 28' communicate with the steam dome 24 through branch pipes 32' and a common supply pipe 33', while the discharge headers 29' again communicate with a common delivery pipe 36' through branch pipes 35'. The supply and delivery pipes 33', 36' may also be provided with suitable stop and safety valves as previously described, and this modified assemblage avoids necessity of penetrating the water chamber of the boiler and may therefore be more readily installed than that of Figs. 1, 2 and 3.

In the further modified superheater assemblage of Figs. 10 and 11, the inlet headers 28'' are disposed at the extreme rear of the boiler near the door 25, while the discharge headers 29'' are located on opposite sides of the boiler near the smoke box 18. The major portions of the heat transfer elements 30'' which connect the headers 28'', 29'', are again disposed within and near the opposite sides of the combustion chamber of the fire-box 20, and these elements 30'' extend forwardly through the boiler flues 19 as indicated. The inlet headers 28'' communicate with the supply pipe 33'' through branch pipes 32'', while the discharge headers 29'' likewise communicate with a common delivery pipe 36'' through branch pipes 35'', and these pipes may also be provided with suitable stop and safety valves. In this assemblage, the use of stay-tubes 31 for accommodating the superheater elements 30'', may again be dispensed with, since these elements may be passed from the inlet headers 28'' into the combustion chamber through the inspection opening which is normally closed by the door 25, and from the interior of the boiler to the discharge headers 29'' through the smoke-box wall.

In the modified assemblage of Fig. 12, the inlet and discharge headers 28''', 29''' may be nested in groups at opposite sides of the forward portion of the fire-box 20, and the elements 30''' are of U-shape instead of S-shaped as in Fig. 1. Instead of utilizing only two heat transfer elements as in the previous type, three or more elements 30''' may be employed in each portion of the superheater. As illustrated, only one superheater unit is utilized at one side of the fire-box 20, and the inlet header 28''' of this single unit communicates directly with the steam dome 24 through a supply pipe 32''', whereas the outlet header 29''' is in direct communication with the

delivery pipe 35". It will be apparent that while Fig. 12 alone discloses the use of a single superheater unit, the other types of units illustrated may also be utilized singly instead of in sets of two.

While the normal mode of installing and utilizing the improved superheaters will be readily apparent from the foregoing description, it may be desirable to present a short description of the operation as applied to Figs. 1, 2 and 3, it being understood that the other modified forms operate in substantially the same manner. When the boiler is operating, the burner 26 is effective in delivering combustible gas to the fire-pit 21, and air is entering this pit through the arch opening 27. The mixture of gas and air thus admitted, is ignited and the gases of combustion pass upwardly through the fire-box 20 along a circuituous path, eventually passing forwardly through the fire-tubes or flues 19 to the stack. During passage of these hot gases through the fire-box 20 and flues 19, heat is absorbed by the water surrounding the fire-box and flues, and the generated steam rises into the dome 24. From the dome 24, the steam passes through the pipes 33, 32 to the inlet headers 28 of the superheater from whence it is distributed to the tubular elements 30. In passing through the elements 30, the temperature of the steam is increased above the temperature of saturated steam of the same pressure, by virtue of the fact that these relatively smaller tubes are exposed directly to the hot gases within the fire-box 20, and the superheated steam is eventually delivered from the discharge headers 29 to the final delivery pipe 36. The deck 50 functions to direct the hot gases and the radiant heat directly against the superheater elements 30, and these elements may be protected against the excessively hot gases by providing covers 47 for the lowermost coils.

When the boiler is shut down, the superheater headers and coils, automatically fill with water, so that the elements 30 will not be destroyed by burning in case the boiler is restarted with a hot fire. This automatic filling of the superheater with water when the boiler is shut down, results from the location of the coils and headers so that when the boiler cools down, the superheater elements act as condensers, the cold air flowing through the burner arch constituting the cooling medium which comes in direct contact with the tubular elements 30. This cooling air acts to quickly condense the steam within the superheater elements, headers, and the piping communicating therewith and located thereabove, and the water of condensation thus produced has been found to be sufficient to produce rapid flooding and complete filling of the horizontal tubular elements 30 of the superheaters. The superheater units may also be quickly drained, if desired, by opening the drain valves preferably applied to the lowest portions of the lower discharge headers 29 as shown in dotted lines in Fig. 1, and the operation of the improved device is entirely automatic since the elements 30 are disposed within the fire-box 20, accidental bursting of an element will do no material damage, and the ruptured element can be readily replaced. By avoiding the use of welded joints in the steam passages, danger of bursting and leakage is reduced to a minimum, and the capacity and efficiency of the superheater units may be quickly varied and enhanced, by properly, adjusting the position of the superheater elements.

The improved superheater is moreover simple

and compact in construction, and has proven highly efficient in commercial operation. It is obviously readily applicable to old or new boilers, either in the field or at the factory, by any boiler maker capable of rolling or expanding boiler tubes, and does not in any manner interfere with the normal use and cleaning of the boiler. The application of the improved superheater to a boiler necessitates only minor changes, and does not require the use of other than standard flues in the boiler structure. The piping arrangement shown in Figs. 1, 2 and 3 not only presents a neat and mechanical appearance, but guards against leakage due to expansion and contraction, and the elements 30 may be held against warping or other displacement by the retainers of Figs. 13 and 14. The improved mounting for the headers 28, 29, shown in Figs. 4 to 7 inclusive, facilitates installation of the units and also adjustment thereof, and a boiler equipped with the improvement may obviously be transported without disturbing the superheater.

It should be understood that it is not desired to limit the invention to the exact details of construction and to the precise mode of installation and use herein shown and described, for various modifications within the scope of the claims may occur to persons skilled in the art.

It is claimed and desired to secure by Letters Patent:

1. In a superheater for a fire-tube boiler having a fire-box and heating flues extending horizontally therefrom, a pair of substantially upright laterally spaced headers disposed externally of the fire-box, and a tubular heating element connecting said headers and comprising superimposed communicating conduit sections disposed within the fire-box in substantially the horizontal planes of some of the flues, said conduit sections being exposed directly to the heating gas and being located closely adjacent to and extending along the side wall of the fire-box substantially the entire length of the latter.

2. In a superheater for a fire-tube boiler having a fire-box and heating flues extending horizontally therefrom, a pair of substantially upright laterally spaced headers disposed externally of the fire-box on each of the opposite sides thereof, and a tubular heating element connecting each pair of said headers and comprising superimposed communicating conduit sections disposed within the fire-box in substantially the horizontal planes of some of the flues, each of said conduit sections being exposed directly to the heating gases and being located closely adjacent to and extending along the adjacent side wall of the fire-box substantially the entire length of the latter.

3. In a superheater for a fire-tube boiler having a fire-box and heating flues extending horizontally therefrom, an inlet header communicable directly with the steam space of the boiler, an outlet header disposed at a lower level than said inlet header, said headers being disposed substantially upright and externally of the fire-box, and a tubular heating element connecting said inlet header with a lower portion of said outlet header and comprising superimposed communicating conduit sections disposed within the fire-box in substantially the horizontal planes of adjacent flues, said conduit sections being exposed directly to the heating gases and being located closely adjacent to and extending along the side wall of the fire-box substantially the entire length of the latter.

4. In a superheater for a fire-tube boiler having a fire-box and heating flues extending hori-

zontally therefrom, an inlet header on each side of the boiler communicating directly with the steam space thereof, an outlet header on each side of the boiler disposed at a lower level than the corresponding inlet header, and a tubular heating element connecting each set of said headers and comprising superimposed communicating conduit sections disposed within the fire-box in substantially the horizontal planes of the adjacent flues, each of said conduit sections being exposed directly to the heating gas and being located closely adjacent to and extending along the adjacent side wall of the fire box for substantially the entire length of the latter.

5. In a superheater for a fire-tube boiler having a fire-box and heating flues extending horizontally therefrom, steam supply and discharge conduits disposed externally of the fire-box, and a tubular heating element connecting said conduits and comprising superimposed communicating conduit sections of relatively small cross-sectional area disposed within the fire-box substantially in alignment with some of the flues, said conduit sections being exposed directly to the heating gas and being located closely adjacent to and extending along the side wall of the fire-box for a considerable distance.

GEORGE S. BLANKENHORN.
